PROCESS OF MANUFACTURE OF TEMPERATURE-SENSITIVE RECORDING PAPER

Dietrich Fritz Arthur Mohnhaupt, Vesenaz, Switzerland, assignor to Permaco S.A., Vesenaz, Switzerland, a corporation of Switzerland

Filed Sept. 8, 1959, Ser. No. 838,401

Claims priority, application Switzerland Sept. 16, 1958
26 Claims. (Cl. 117—36.7)

For the graphic representation of measured values, particularly those which change very rapidly, temperature-sensitive recording papers are frequently employed. These usually consist of a dark (generally black) paper to which a light-colored (generally white) covering layer is applied. On contact with a suitably heated stylus the covering layer melts or sinters so that the dark background becomes visible and the effect of a dark marking on a light ground is produced.

The light temperature-sensitive layer usually consists of an organic highly polymerized material which is applied in the form of a solution or dispersion to the dark carrying paper. On simply drying the solution or dispersion which is applied, a white layer is not directly formed, but in general a lacquer-like coating, through which the dark background is visible. This coating was hitherto caused to become white by conducting a strong current of cold air over the liquid layer on the paper. Owing to the rapid evaporation of the solvent caused thereby, the cold due to the evaporation produces effects which cause moisture in the air to be deposited on the layer and partly in the interior thereof. The whitening produced in this manner is not uniform and is dependent on many chance effects.

A second method of producing the whitening is based on the formation of very many very small hollow spaces in the interior of the layer during the evaporation of the solvent. These hollow spaces are only formed when the solvent is evaporated sufficiently rapidly before the solid constituents of the layer become coagulated. For this reason only very dilute solvents with a solid content up to approximately 6 percent by weight can be used, because the solid highly polymerized constituents of the layer possess the property of tenaciously retaining the solvent. When the layer is subjected to the necessary rapid drying by blowing on to it a strong current of air, however, waves are formed on the liquid layer because its low viscosity does not offer any appreciable resistance to the current of air. On continued drying the layer can break at the troughs of the waves, or in any case the thickness of the layer is not uniform.

The present invention obviates these disadvantages and enables a temperature-sensitive recording paper having an absolutely uniform layer and very good white shade to be made. According to the invention, the process for manufacturing temperature-sensitive recording papers, which shall now be explained having reference to a flow diagram illustrating said process in the accompanying drawing, characterized in that a light-colored organic, highly polymerized substance "A" is dissolved in a low boiling solvent "B" and the resulting solution ("A" in "B") is mixed with a higher boiling organic liquid "C," which is inert towards paper and in which the above-mentioned substance is insoluble, the higher boiling liquid being added in an amount such that the highly polymerized substance is not precipitated and the total mixture (C+A/B) has a solid content of 6 to 20 percent by weight. A dark carrying paper "P" is then coated (step I in the accompanying flowsheet) with a layer of this mixture and first the low boiling solvent ("B"; step II)

2

and after this the higher boiling liquid ("C"; step III) is evaporated.

The highly polymerized organic substance which forms the coating layer is dissolved in a low boiling point solvent, for example, acetone, methylacetate, tetrahydrofuran, dimethylacetal, or methylenechloride. As much of the higher boiling organic liquid, in which the substance which forms the layer is insoluble, is added so as not to cause precipitation of the substance. After application to the carrying paper the solvent is mainly evaporated, so that the substance which forms the coating layer is precipitated as a finely divided light-colored precipitate in the organic liquid. On continued evaporation of the organic liquid, the substance which forms the coating layer combines intimately with the surface of the carrying paper, an extremely good adherence being obtained.

The whitening of the layer depends therefore on the precipitation of very small particles of solid deposited at random in an indifferent liquid.

The time of evaporation of the solvent should be between 1.8 and 2.4, preferably 2, that of the organic liquid, should be between 2.8 and 4, preferably 3, as compared with that of diethylether which is taken to be equal to 1.

The indifferent organic liquid should have no chemical affinity for the constituents of the carrying paper because experiments have shown that otherwise distortion and shrinking of the carrying paper occur, whereby the adherence of the temperature-sensitive layer considerably decreases. Liquids which are not useful are, for example, substances having OH-groups (alcohols and acids). In particular no water should be present. Substances which can be used with advantage are aliphatic hydrocarbons, for example, cyclohexane, hexane, heptane, benzine and the like.

As the substances which form the coating layer, all highly polymerized organic substances are suitable, provided they are soluble in the above-mentioned solvents and insoluble in the above-mentioned liquids and possess a satisfactory white shade or color and have, either in the pure form or in mixtures, a melting or sintering point which is between 80° C. and 220° C. Suitable substances are for example cellulose esters, cellulose ethers, polystyrene, polyvinylacetate, ketone resins, derivatives of colophony, phenol-formaldehyde resins, polyvinylchloride, polyvinylidenechloride, polymethacrylate, coumarone resins, etc.

Since the concentration of the layer forming substance in the present process amounts to 6 to 20% and is preferably 10%, the solution has a viscosity which is comparable with that of glycerine. Owing to this, the formation of waves and cracks on drying with air is prevented and a layer of uniform thickness is formed.

As previously mentioned a mixture of high polymerized substances may be used as the substance which forms the coating layer. By altering the composition of the mixture a suitable melting point for the mixture, which is adapted to suit the requirements of the recording apparatus, can be obtained. Also by addition of low melting point waxes or resins and softeners the melting point of the layer can be adjusted as desired.

The whitening of the layer can be accelerated by removing the solvent by means of a current of air at a temperature of about 35° C. instead of with a current of cold air. After this, the higher boiling organic liquid can be evaporated by a current of hot air, the temperature of which is below the melting temperature of the solid constituents forming the coating layer. Therefore a current of air at a temperature of 20 to 40° C., preferably 35° C., is first directed on to the layer until this appears white and after this a current of air at a tem-

perature of 40 to 100° C., preferably 75° C., is directed on the layer until the higher boiling liquid is completely evaporated.

An advantageous process in accordance with the invention is, for example, to use polyisobutylene as the highly polymerized substance and pentane, hexane or benzine as the lower boiling solvent, and ethylacetate or methyl-ethylketone as the higher boiling organic liquid.

There is a limit to the speed with which the values to be registered can be recorded. This is reached when the amount of heat transmitted from the stylus to the temperature-sensitive coating layer is no longer sufficient to cause the layer to become transparent. The coating layers produced by the methods of the invention can be caused to respond in a considerably shorter time if two additional precautions are used either singly or in combination; these enable the time of response of the paper to be reduced by about two orders of magnitude.

The first precaution enables the thickness of the temperature-sensitive layer to be reduced without detracting from the degree of whiteness. For this purpose there is added to the solid constituents of the coating layer an optical brightener which has the property of causing a grey surface to appear white. A temperature-sensitive layer made by the process described cannot be made thinner than 15 to 10 μ without the dark background appearing through it. However, if a small amount of an optical brightener is added, the thickness of the layer can be reduced to 5 μ while maintaining the necessary degree of whiteness. The time of response as compared with a layer having a thickness of 15 μ is reduced by about three times.

Optical brighteners are known in the textile industry. They are frequently used in order to cause textiles which have frequently been washed and have a grey appearance to appear white again. For the purposes of the present invention there may be used derivatives of benzothiazole, stilbene and triazine (see British Patent No. 683,895, Swiss Patent No. 275,140 and Belgian Patent No. 540,323) which are known in commerce under the registered trademark "Blankophor" of Farbenfabriken Bayer A.G., and are used as optical brighteners.

The second additional precaution is based on the idea of producing the heat necessary for making the layer transparent by exothermic chemical reaction in the layer itself, the stylus requiring only to be heated to the reaction temperature at the place of contact. Suitable reactions which evolve the necessary heat are oxidation and neutralization processes. For the present purpose it is advantageous if the speed of the chemical reaction increases greatly with rise of temperature. Solid substances in general react with one another only extremely slowly, whereas they can react very rapidly at temperatures above their melting points.

Strong oxidizing agents, such as peroxides, for example, are often very stable in the solid state and at room temperature whereas they decompose very rapidly at the temperature of their melting point and slightly above this temperature. In the presence of a reducing agent they evolve atomic oxygen which liberates more heat on oxidation than molecular oxygen. If peroxy acids are used in the presence of bases having a reducing action, for example certain amines, the neutralization also acts as an additional supplier of heat of 13.7 kcal./mol.

When the hot stylus makes a superficial contact for a short time with the coating layer, the nearest part of the layer melts, which part contains in addition to the highly polymerized organic substance, the peroxy acid

(or an inorganic peroxy acid) and a reducing amine R'-NH₂ (or a suitable inorganic compound) and in

some cases also an optical brightener. The reactions which then take place are substantially as follows:

(1)

(2)

The heat produced is sufficient to allow the layer to melt or become glazed down to the dark background. There is thus formed a visible writing trace where the layer without the chemical reactions would be only quite superficially melted.

It is advantageous to use substances, the reaction products of which remain liquid at the reaction temperature, that is to say at a temperature of about 100° C., in order to save energy which must be expended in melting the substances.

By altering the nature and concentration of the oxidizing and reducing agents the time of response of the layer can be considerably varied. The concentrations, however, must not be so high that spontaneous reactions occur.

By suitable combination of the process of the invention with the two precautions described above record papers can be made which have a time of response of from 2.5 to 0.1 milliseconds, whereas the hitherto known record papers had a time of response of above 10 milliseconds.

The invention will now be explained in greater detail with the aid of the following examples.

Example 1

16.5 g. of celluloseaceto-butyrate and 0.8 g. of phthalic acid-dicyclohexylester are dissolved in 120 g. of acetone. 80 g. of cyclohexane are then added with stirring. This mixture is applied in a thickness of 0.05 mm. to a black carrying paper by means of rollers, and is blown for 10 seconds with air at a temperature of 35° C. and then for 10 seconds with air at 75° C. The layer obtained responds at a temperature of about 120° C.

Example 2

11 g. of celluloseaceto-butyrate and 11 g. of ethyl cellulose are dissolved in 100 g. of tetrahydrofuran and then 100 g. of benzine having a boiling range of 80 to 100° C. are added while stirring. The further treatment is the same as in Example 1. The white layer obtained responds at a temperature of approximately 140° C.

Example 3

20 g. of polystyrene and 2.2 g. of a ketone resin (made from cyclohexanone and methylcyclohexanone) are dissolved in 120 g. of methylacetate. Then 80 g. of heptane are added while stirring. The application and drying of the coating takes place as in Example 1. The layer obtained responds at a temperature of about 100° C.

Example 4

22 g. of polyisobutylene (molecular weight about 200,000) are dissolved in 110 g. of hexane. 90 g. of ethylacetate are then added with stirring. The further treatment takes place as in Example 1. The layer obtained responds at a temperature of about 150° C.

Example 5

14 g. of celluloseaceto-butyrate, 0.7 g. of phthalic acid-dicyclohexylester and 2.6 mg. of an optical brightener (Blankophor) are dissolved in 120 g. of acetone. Then 80 g. of cyclohexane are added with stirring. The further treatment takes place as in Example 1, the thickness of the applied layer of solution being such that a layer of 5 to 8 μ in thickness is obtained. This has a time of response of about 2.5 milliseconds with a stylus heated to 220° C.

5

Example 6

14 g. of celluloseaceto-butyrate, 0.7 g. of phthalic acid-dicyclohexylester, 1.6 g. of monoperoxyphthalic acid and 1 g. of meta-aminophenol are dissolved in 120 g. of acetone. Then 80 g. of cyclohexane are added with stirring. The further treatment is the same as in Example 1. The layer obtained has a time of response of only 0.25 milliseconds on contact with a stylus heated to 220° C.

Example 7

2.6 mg. of an optical brightener (Blankophor) are added to the solution obtained in Example 6. The layer is applied in the same way as in Example 1 and has a thickness of about 5 to 8 μ . The time of response is from 0.1 to 0.18 millisecond.

Example 8

18 g. of polystyrene, 2 g. of a ketone resin (made from cyclohexanone and methylcyclohexanone), 0.65 g. of dibenzoylperoxide and 1.5 g. of N-dimethyl-meta-aminophenol are dissolved in 120 g. of methylacetate. After addition of 80 g. of heptane the layer is applied to black paper as in Example 1.

Example 9

1.5 mg. of optical brightener (Blankophor) are added to the mixture described in Example 8 and the mixture is applied to black paper in the manner described in Example 1, the layer having a thickness of 5 to 8 μ . This has a time of response of 0.1 to 0.15 millisecond on contact with a stylus heated to 220° C.

What I claim is:

1. A process for manufacturing temperature-sensitive recording paper having a light-colored coating layer on a dark carrier paper base, comprising admixing with the solution of a polymerized organic substance having a sintering point of from about 80° to 220° C. in an organic solvent therefor having a boiling point lower than the sintering point of said polymerized material, an organic liquid free from hydroxyl groups which has a boiling point above the boiling point of said organic solvent and below the sintering point of said polymeric material, which is inert toward said paper base, and in which said polymerized material is insoluble, said liquid being added in such amounts to said solution that said polymerized material is not precipitated therefrom, and that the solids content of the resulting mixture is from about 6 to 20% by weight; applying said resulting mixture on said paper base; heating the resulting layer of said mixture on said paper base to evaporate substantially exclusively said solvent therefrom, thereby forming a finely divided gray to white precipitate of said polymerized substance in said inert liquid on said paper base; and then heating further to such temperature as to evaporate said inert liquid therefrom and forming a gray to white coating of said polymerized substance on said paper base.

2. The process as described in claim 1, wherein said resulting mixture is applied on said paper base in such amount that the final gray to white coating of said polymerized substance on said paper base has a thickness of at least 10 microns to 15 microns and more.

3. The process described in claim 1, wherein said polymerized organic substance is selected from the group consisting of cellulose esters, cellulose ethers, polystyrene, polyvinylacetate, ketone resins, colophony derivatives, formaldehyde resins, polyvinylidene chloride, polyvinyl chloride, polymethacrylate, coumarone resins and polyisobutylene.

4. The process as described in claim 3, wherein said resulting mixture is applied to said paper base in such amount that the final gray to white coating of said polymerized substance on said paper base has a thickness of at least 5 microns.

5. A process according to claim 1, wherein the low boiling solvent is selected from the group consisting of

6

acetone, methylacetate, tetrahydrofuran, dimethylacetal and methylenechloride, and the higher boiling organic liquid is selected from the group consisting of cyclohexane, hexane, heptane and benzene.

5 6. A process according to claim 1, wherein the low boiling solvent is selected from the group consisting of pentane and hexane, and the higher boiling organic liquid is selected from the group consisting of ethylacetate and methyl ethyl ketone, and the polymerized organic substance is polyisobutylene.

10 7. A process for manufacturing temperature-sensitive recording paper having a light-colored coating layer on a dark carrier paper base, comprising admixing with the solution of a polymerized organic substance having a sintering point of from about 80° to 220° C. in an organic solvent therefor having a boiling point lower than the sintering point of said polymerized material, an organic liquid free from hydroxyl groups which has a boiling point above the boiling point of said organic solvent

15 and below the sintering point of said polymeric material, which is inert toward said paper base, and in which said polymerized material is insoluble, said liquid being added in such amounts to said solution that said polymerized material is not precipitated therefrom, and that the solids content of the resulting mixture is from about 6 to 20%

20 by weight; applying said resulting mixture on said paper base; directing a current of air at a temperature of from about 20° to 40° C. on to the surface of the resulting layer of said mixture on said paper base to evaporate substantially exclusively said solvent therefrom, until said

25 layer is whitened thereby forming a finely divided precipitate of said polymerized substance in said inert liquid on said paper base; and then directing another current of air at a temperature of from about 40 to 100° C. on to the surface of the resulting layer on said paper base, thereby evaporating said inert liquid therefrom and forming a gray to white coating of said polymerized substance on said paper base.

30 8. A process for manufacturing temperature-sensitive recording paper having a light-colored coating layer on a dark carrier paper base, comprising admixing with the solution of a polymerized organic substance having a sintering point of from about 80° to 220° C. and an optical brightener in an organic solvent therefor having a boiling point lower than the sintering point of said polymerized material, an organic liquid free from hydroxyl groups which has a boiling point above the boiling point of said organic solvent and below the sintering point of said polymeric material, which is inert toward

35 said paper base, and in which said polymerized material is insoluble, said liquid being added in such amounts to said solution that said polymerized material is not precipitated therefrom, and that the solids content of the resulting mixture is from about 6 to 20% by weight;

40 35 applying said resulting mixture on said paper base; heating the resulting layer of said mixture on said paper base to evaporate substantially exclusively said solvent therefrom, thereby forming a finely divided gray to white precipitate of said polymerized substance in said inert liquid on said paper base; and then heating further to such temperature as to evaporate said inert liquid therefrom and forming a gray to white coating of said polymerized substance on said paper base.

45 35 9. The process described in claim 8, wherein the optical brightener is selected from the group consisting of benzthiazole optical brighteners, stilbene optical brighteners and triazine optical brighteners.

50 40 10. A process for manufacturing temperature-sensitive recording paper having a light-colored coating layer on a dark carrier paper base, comprising admixing with the solution of a polymerized organic substance having a sintering point of from about 80° to 220° C. in an organic solvent therefor having a boiling point lower than the sintering point of said polymerized material, an oxidizing agent selected from the group consisting of acid

55 45 70 75

peroxides and peroxyacids, a reducing amine capable of reacting with said oxidizing agent at a temperature above their melting points, with evolution of heat, and an organic liquid free from hydroxyl groups which has a boiling point above the boiling point of said organic solvent and below the sintering point of said polymeric material, which is inert toward said paper base, and in which said polymerized material is insoluble, said liquid being added in such amounts to said solution that said polymerized material is not precipitated therefrom, and that the solids content of the resulting mixture is from about 6 to 20% by weight; applying said resulting mixture on said paper base; heating the resulting layer of said mixture on said paper base to evaporate substantially exclusively said solvent therefrom, thereby forming a finely divided gray to white precipitate of said polymerized substance in said inert liquid on said paper base; and then heating further to such temperature as to evaporate said inert liquid therefrom and forming a gray to white coating of said polymerized substance on said paper base.

11. The process described in claim 10, wherein said oxidizing agent is monoperoxyphthalic acid and said reducing amine is meta-aminophenol.

12. The process described in claim 10, wherein said oxidizing agent is dibenzoylperoxide and said reducing amine is N-dimethyl-meta-aminophenol.

13. A process for manufacturing temperature-sensitive recording paper having a light-colored coating layer on a dark carrier paper base, comprising admixing with the solution of a polymerized organic substance having a sintering point of from about 80° to 220° C., an optical brightener, and an oxidizing agent selected from the group consisting of acid peroxides and peroxyacids, and a reducing amine capable of reacting with said oxidizing agent at a temperature above their melting points with evolution of heat in an organic solvent therefor having a boiling point lower than the sintering point of said polymerized material, an organic liquid free from hydroxyl groups which has a boiling point above the boiling point of said organic solvent and below the sintering point of said polymeric material, which is inert toward said paper base, and in which said polymerized material is insoluble, said liquid being added in such amounts to said solution that said polymerized material is not precipitated therefrom, and that the solids content of the resulting mixture is from about 6 to 20% by weight; applying said resulting mixture on said paper base; heating the resulting layer of said mixture on said paper base to evaporate substantially exclusively said solvent therefrom, thereby forming a finely divided gray to white precipitate of said polymerized substance in said inert liquid on said paper base; and then heating further to such temperature as to evaporate said inert liquid therefrom and forming a gray to white coating of said polymerized substance on said paper base.

14. The process described in claim 13, wherein said optical brightener, said oxidizing agent and said amine are not insoluble in said organic liquid.

15. A coating bath for the manufacture of temperature-sensitive recording paper, consisting essentially of a solution of a polymerized organic substance having a sintering point of from about 80° to 220° C. in an organic solvent therefor having a boiling point lower than the sintering point of said polymerized material, and an organic liquid free from hydroxyl groups which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 20% by weight.

16. The coating bath described in claim 15, wherein said polymerized organic substance is selected from the

group consisting of cellulose esters, cellulose ethers, polystyrene, polyvinylacetate, ketone resins, colophony derivatives, formaldehyde resins, polyvinylidene chloride, polyvinyl chloride, polymethacrylate, coumarone resins and polyisobutylene.

17. The coating bath according to claim 15, wherein the low boiling solvent is selected from the group consisting of acetone, methylacetate, tetrahydrofuran, dimethylacetal and methylenechloride, and the higher boiling organic liquid is selected from the group consisting of cyclohexane, hexane, heptane and benzine.

18. The coating bath according to claim 15, wherein the low boiling solvent is selected from the group consisting of pentane and hexane, and the higher boiling organic liquid is selected from the group consisting of ethylacetate and methyl ethyl ketone, and the polymerized organic substance is polyisobutylene.

19. A coating bath for the manufacture of temperature-sensitive recording paper, consisting essentially of a solution of a polymerized organic substance having a sintering point of from about 80° to 220° C. and an optical brightener in an organic solvent therefor having a boiling point lower than the sintering point of said polymerized material, and an organic liquid free from hydroxyl groups

20 to 25 which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 20% by weight.

formed from a layer of a mixture of the solution of said polymerized organic substance in an organic solvent therefor having a boiling point lower than the sintering point of said polymerized material, with an organic liquid free from hydroxyl groups which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 20% by weight, in which layer said polymerized substance has first been precipitated by evaporation substantially only of said solvent, and the final coating has been formed by subsequent evaporation of said organic liquid.

23. A temperature-sensitive recording paper consisting essentially of a dark carrier paper base and a coating thereon of a finely divided gray to white precipitate of a polymerized organic substance having a sintering point of from about 80 to 220° C. and being selected from the group consisting of cellulose esters, cellulose ethers, polystyrene, polyvinylacetate, ketone resins, colophony derivatives, formaldehyde resins, polyvinylidene chloride, polyvinyl chloride, polymethacrylate, coumarone resins and polyisobutylene; said coating having a thickness of at least about 10 to 15 microns, and being formed from a layer of a mixture of the solution of said polymerized organic substance in an organic solvent therefor having a boiling point lower than the sintering point of said polymerized material, with an organic liquid free from hydroxyl groups which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 20% by weight, in which layer said polymerized substance has first been precipitated by evaporation substantially only of said solvent, and the final coating has been formed by subsequent evaporation of said organic liquid.

24. A temperature-sensitive recording paper consisting essentially of a dark carrier paper base and a coating thereon of a finely divided gray to white precipitate of a polymerized organic substance having a sintering point of from about 80 to 220° C. and an optical brightener; said coating having a thickness of at least about 5 microns, and being formed from a layer of a mixture of the solution of said polymerized organic substance in an organic solvent therefor having a boiling point lower than the sintering point of said polymerized material, with an organic liquid free from hydroxyl groups which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 20% by weight, in which layer said polymerized substance has first been precipitated by evaporation substantially only of said solvent, and the final coating

has been formed by subsequent evaporation of said organic liquid.

25. A temperature-sensitive recording paper consisting essentially of a dark carrier paper base and a coating thereon of a finely divided gray to white precipitate of a polymerized organic substance having a sintering point of from about 80 to 220° C., an oxidizing agent selected from the group consisting of acid peroxides and peroxyacids, and a reducing amine capable of reacting with said oxidizing agent at a temperature above their melting points with evolution of heat; said coating having a thickness of at least about 10 to 15 microns, and being formed from a layer of a mixture of the solution of said polymerized organic substance in an organic solvent therefor having a boiling point lower than the sintering point of said polymerized material, with an organic liquid free from hydroxyl groups which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 20% by weight, in which layer said polymerized substance has first been precipitated by evaporation substantially only of said solvent, and the final coating has been formed by subsequent evaporation of said organic liquid.

26. A temperature-sensitive recording paper consisting essentially of a dark carrier paper base and a coating thereon of a finely divided gray to white precipitate of a polymerized organic substance having a sintering point of from about 80 to 220° C., an optical brightener, an oxidizing agent selected from the group consisting of acid peroxides and peroxyacids, and a reducing amine capable of reacting with said oxidizing agent at a temperature above their melting points with evolution of heat; said coating having a thickness of at least about 5 microns, and being formed from a layer of a mixture of the solution of said polymerized organic substance in an organic solvent therefor having a boiling point lower than the sintering point of said polymerized material, with an organic liquid free from hydroxyl groups which has a boiling point above the boiling point of said organic solvent and below the sintering point of said polymeric material, which is inert toward said paper base, and in which said polymerized material is insoluble, said liquid being contained in such amounts in said solution that said polymerized material is not precipitated therefrom, and that the solids content of the resulting mixture is from about 6 to 50% by weight, in which layer said polymerized substance has first been precipitated by evaporation substantially only of said solvent, and the final coating has been formed by subsequent evaporation of said organic liquid, said recording paper having a time response of from about 2.5 to 0.1 milliseconds.
